UNITED STATES PATENT OFFICE

2,666,658

MOTION TRANSMITTAL AND SEALING
MEANS THEREFOR

Howard H. Laucks, Boonton, N. J., assignor to
Bendix Aviation Corporation, Teterboro, N. J.,
a corporation of Delaware

Application October 19, 1949, Serial No. 122,159

1 Claim. (Cl. 286—1)

1

The present invention relates to motion indicating means and sealing means for the same.

One of the problems in the design and construction of equipment such as servos, valves, motors or the like, wherein a movable member reciprocates or rotates in a high pressure chamber, is to devise a means of transmitting values referable to said member outside said chamber and to adequately seal said means.

In certain applications, this problem has been partially solved by use of a stuffing box. But this solution tends to impose frictional load upon the rod, and further difficulty is encountered in providing an absolute seal where the shaft is rotating or sliding.

The present invention contemplates providing a very small diameter tube with a relatively long length. Within this tube is a close fitting wire. High pressure oil at the chamber end of the tube is thus confronted with a very long leakage path of small cross-sectional area. Due to the small clearance present, the wire would be free to move in the tube, thereby relaying a motive signal.

It is, therefore, one of the objects of the present invention to provide means for transmitting motion from a movable member in a high pressure chamber to a position indicating device outside said chamber and to do so in a novel and effective manner.

Another object of the invention is to provide reliable sealing means for the foregoing motion transmitting means.

Another object of the invention is to provide a seal of the above-indicated nature which will permit a certain amount of dimensional variation between the moving member and its guiding surfaces.

Still another object of the invention is to provide motion transmitting means and sealing means therefor that will be simple, easy and economical to manufacture, maintain and install, and yet positive and reliable in operation.

The foregoing and other objects and advantages will appear more fully hereinafter from a consideration of the detailed description which follows, taken together with the accompanying drawing wherein one embodiment of the invention is illustrated by way of example. It is to be expressly understood, however, that the drawing is for the purposes of illustration only and is not to be construed as defining the limits of the invention.

Referring to the drawings, wherein like reference characters designate like parts,

The figure is an elevation view in section of a typical device incorporating the invention.

2

In the single figure drawing, a casing 10 as of a valve, servo, pump or the like encompasses a fluid filled high pressure chamber 12 wherein a movable member 14 reciprocates. The pressure chamber 12 is sealed off at one end by means of a closure plug, or end wall, 16 that is held in place by the pins 18 and 20. A thru hole, or bore, 22 in the closure plug 16 leads into a larger diameter hole, or bore, 23 through the plug 16 and the pins 18 and 20, and communicates with the pressure chamber 12. A thin walled and relatively long tube 24 is firmly cantilevered into the hole 22, and extends to the end of hole 23 in the plug 16. Within said tube 24 a very close fitting wire 26 is passed and secured at one end as at boss 28 to the movable member 14. The opposite end 30 of the wire 26 leads to some position indicating device not shown here, common to the art, such as a gage, counter, or the like.

Having thus described the invention, it will now be apparent to those skilled in the art that when the reciprocating member 14 moves, it will transmit said movement to the wire 26 outside of the high pressure chamber 12 immediately and without loss in magnitude, to said indicating device to give indicia referable to the moving member 14.

Although the wire 26 fits snugly within the tube 24, a minimum amount of clearance therebetween is nevertheless present. Said minimum clearance between the wire 26 and the tube 24 affects a reliable seal since the fluid in the high pressure chamber 12 is confronted with a relatively long leakage path of negligible cross-sectional area and thereby finds itself effectively trapped.

It is particularly to be noted that since the tube 24 is secured at the cantilevered end only, a certain amount of flexibility therein will be available at the other end in proximity to the chamber 12. Said flexibility will suffice to permit a reasonable amount of dimensional misalignment between the point at which the wire is secured to the moving member 14, and the point at which the wire protrudes through the closure plug 16.

There are thus provided simple and effective means for transmitting motion from a movable member in a high pressure chamber to a position indicating device outside that chamber that are adequately sealed, and which do not penalize the moving member with frictional loads.

Although only a single embodiment and application of the invention has been illustrated and described, other changes and modifications in the form and relative arrangements of parts which will be apparent to those skilled in the

art may be made without departing from the spirit and scope of the invention.

What is claimed is:

In combination, a pressure chamber having a pressurized fluid therein and a wall closing one end thereof, a member movable in said pressure chamber, said end wall including a through bore having a relatively short reduced diameter portion adjacent the outer end thereof, a relatively long tube disposed in said bore, said tube firmly secured at the outer end only in the reduced diameter portion of the bore and communicating at its inner end with said pressure chamber, said tube being circumferentially spaced from the walls of the through bore throughout its unsecured length, a wire connected at one end to said movable member and extending through said tube, said tube and wire having a minimum

10

15

amount of clearance therebetween to define a relatively long path of negligible cross-sectional area along the length of said tube between said pressure chamber and the exterior thereof and wherein the pressurized fluid is trapped to thereby seal said pressure chamber.

HOWARD H. LAUCKS.
